HYDROAIRPLANE LANDING-GEAR.

1,382,421.

Specification of Letters Patent. Patented June 21, 1921.

Application filed October 10, 1918. Serial No. 257,657.

To all whom it may concern:

Be it known that we, WILLIAM L. GILMORE and JOSEPH F. MEADE, citizens of the United States, residing at Roosevelt, in the county 5 of Nassau and State of New York, have invented certain new and useful Improvements in Hydroairplane Landing-Gears, of which the following is a specification.

Our invention relates to airplanes and 10 more particularly to improvements in airplane landing gears.

An object of the invention is to provide a landing gear for seaplanes and hydroairplanes which will offer minimum head resistance commensurate with strength. In gaining 15 this end the number of landing gear struts heretofore required is diminished and in lieu of the more or less conventional V-strut arrangement single center struts are provided. These struts are arranged one 20 aft of the other in the longitudinal vertical plane of the fore and aft axis of the pontoon or float and constitute the only strut connection between it (the pontoon) and that 25 part or portion of the craft beneath which the pontoon is supported. In addition to the two center struts brace wires are provided. These wires are arranged respectively at opposite sides of the float and between the center struts, the former caring 30 for laterally directed shocks and the latter for vertically directed shocks in hydroplaning and landing. The wires, at their ends, are carried into the pontoon or float for 35 connection with the lower strut ends and for the additional purpose of diminishing the head resistance or drag. Moreover, since the wires are anchored at or near the lower strut ends maximum strength is accorded 40 the struts.

The invention is further characterized by an improved strut mounting. Since but two center struts are provided it is incumbent 45 that they be accorded maximum strength. At their upper ends the struts are carried into the fuselage or body of the craft and at their lower ends into the pontoon or float. Preferably the strut ends are bifurcated to straddle on the one hand a structural 50 element of the fuselage and on the other hand a structural element of the float. This, together with the fact that socket fittings are provided at the strut ends and the further fact that the brace wires

are anchored to such fittings enables us to 55 utilize the full strength of each strut with the resultant advantage that the number of struts is reduced as pointed out above. Other constructional details and refinements 60 will be hereinafter set forth.

Of the drawings:

Figure 1 is a side elevation of a seaplane having a landing gear as herein set forth;

Fig. 2 is a front end elevation of the machine;

Fig. 3 is a longitudinal vertical sectional view of the pontoon and fuselage showing the strut arrangement and mounting; also the interior construction of the pontoon;

Fig. 4 is a transverse vertical sectional 70 view of the pontoon and fuselage showing the strut mounting used from the front;

Fig. 5 is a similar view emphasizing the difference in length between the front and rear struts of the landing gear; also detailing the mounting of the longer of the two;

Fig. 6 is an enlarged perspective view of the mounting at the foot of the rear vertical strut;

Fig. 7 is an enlarged transverse section on 80 the line 7-7 of Fig. 4;

Fig. 8 is a fragmentary sectional view showing the connection between the forward center strut and the fuselage, and

Fig. 9 is a front elevation of that portion 85 of the connection illustrated in Fig. 8.

In the embodiment of the invention selected for illustration the landing gear is shown as constituting a part of a single float seaplane or hydroairplane in which the float 90 or pontoon is mounted directly beneath the fuselage or body. It is to be understood however that we do not intend to limit ourselves to any particular type of machine and the strut arrangement and structural 95 details of the invention may be equally as well used in connection with a twin or multiple float machine or in connection, in so far as certain of the details are concerned, with land machines. Moreover, although a particular construction of fuselage is shown and a particular construction of pontoon is shown, the constructional details of both of these parts of the machine are immaterial.

The float or pontoon illustrated, designated in its entirety by the numeral 10, is provided with two rearwardly facing steps 11 and 12 and a V-bottom 13 of hydroplan-

ing form. It is of a good streamline shape in longitudinal section and is preferably equipped with a single longitudinal bulk head 14 extending substantially the full depth of the pontoon. This bulk head (see Fig. 3) is lightened as at 15 at or near its ends and is of a length sufficient to extend substantially the full length of the float. In addition to the bulk head 14 the skeleton of 10 the pontoon framework comprises a keelson 16, chine stringers 17, bilge stringers 18, deck stringers 19 and transverse bulk heads 20, the latter being spaced longitudinally throughout the full length of the pontoon to 15 strengthen it and at the same time divide it into a number of non-communicating or rather independently water-tight compartments 21.

The fuselage of the machine, designated in 20 its entirety by the numeral 22, like the pontoon 10, is of good streamline section. It comprises upper longerons 23, lower longerons 24, transverse diaphragms 25, fuselage struts 26 and wiring 27. The diaphragms 25 however are the only elements of the fuselage which in any way enter into and form 25 a part of the landing gear. At its tail end the fuselage is equipped with a vertical rudder 28, elevator flaps 29, vertical stabilizer 30 and horizontal stabilizer 31, and at its 30 forward end with an engine bed 32 for the power plant which includes, in addition to the motor (not shown) a radiator 34 and propeller 35, the latter being preferably the 35 tractor four-bladed type.

The wing structure of the machine is of 36 the biplane type and comprises upper wings 36, lower wings 37, wing struts 38 and wiring 39. The manner in which the wires are 40 arranged and in which the struts are constructed is the subject matter of an application already on file, *i. e.* application Serial No. 226,848, filed April 5, 1918.

The landing gear, in addition to the float 45 or pontoon 10 above generally described, comprises a forward landing gear strut 40 and a rear landing gear strut 41. The forward landing gear strut 40 is inclined slightly in a fore and aft direction to better 50 withstand the heavy hydroplaning and landing impacts incurred during the operation of the machine. It is shorter than the rear strut 41 and at its upper end is directly fastened to the diaphragm 25 of the fuselage. 55 In this connection it will be noted that the diaphragm 25 is so situated that it not only supports the engine bed 32 from beneath, but for obvious reasons, projects below the horizontal plane of the lower longerons to offer 60 a substantial bearing surface for the upper end of the forward strut. This construction is best illustrated in Fig. 4. The strut 40, in addition to being shorter than the strut 41 is provided at its upper end with a bifur- 65 cation 42 within which the extended portion

of the diaphragm 25 is seated, the periphery of the diaphragm, at its lowermost point directly engaging the inner end of the bifurcation or slot. Such a construction is not only preferred because of the increased 70 strength which it offers but because of the further fact that the strut is fastened to and inside the fuselage at a point directly beneath the weight mass of the motor. A deep 75 socket fitting 43 of a two-part construction provides a fastening means for the strut 40. These fitting parts are arranged upon opposite faces of the diaphragm 25 to which they are bolted. Being deep the fitting affords 80 an adequate means for holding the strut in place.

The rear strut 41, unlike the forward strut 40, is carried into the fuselage, preferably to a point in horizontal alignment with the upper longerons 23. It extends substantially 85 vertical, that is, without inclination, and is fastened inside the fuselage by special fittings, one of which is illustrated in Fig. 6 and designated 44. These fittings are provided at two points along the strut length 90 and with the internal fuselage wiring rigidly hold the strut in its vertical position and at the same time fixed relatively to the fuselage itself.

Both struts, 40 and 41, lie in the longitudinal 95 vertical plane of the longitudinal center line of the pontoon. In fact, they constitute the only strut connection between the pontoon and that part or portion of the craft beneath which it is supported. At 100 their lower ends the struts are carried into the pontoon for a substantial portion of its depth, preferably its full depth as indicated in Fig. 3. The lower ends of the struts are also bifurcated as indicated at 45 in a fore 105 and aft direction to straddle the center longitudinal bulk head 14 of the pontoon. Socket fittings 47 are also provided for the lower ends. These fittings instead of being constructed in two-part form comprise, each, 110 four fitting sections, two sections being arranged upon each side of the longitudinal bulk head 14. In Fig. 6 the four-part fitting provided at the foot of the rear center strut 41 is detailed. It will be noted that one of the fitting parts is located in each of the four 90° angles formed by the intersecting bulk heads 14 and 20 of the pontoon, as in the preferred embodiment of the invention 115 the struts 40 and 41 both enter the pontoon 120 at points in alignment with the bulk heads 20 thereof. The bulk heads 20 however, unlike the center longitudinal bulk heads 14 are interrupted at the strut points as the struts are bifurcated only in a fore and aft 125 direction. The fitting parts are directly fastened to the bulk heads as indicated at 48 by through bolts common to opposed fitting parts.

The socket fitting arrangement, above de- 130

scribed, is duplicated, as intimated, at the foot of each strut although in one instance the socket fitting is inclined in a fore and aft direction to receive the inclined strut 5 while in the other instance it extends substantially vertical to accommodate the vertical strut. Preferably the sockets 47 are open at their upper ends to receive the struts 40 and 41 as such a construction will enable 10 the pontoon to be secured to the struts after it is completely finished. Otherwise work upon the pontoon would be required after its adjustment to the machine. In this connection the snug fit between the strut ends, 15 which are tapered, and the complementary sockets within which the tapered strut ends are seated constitutes, in connection with band fittings 49 and the wiring hereinafter described, the only fastening for the pontoon. 20

The wiring for the landing gear, see Figs. 3, 4 and 5 comprises lateral brace wires 50 and fore and aft brace wires 51. The lateral brace wires 50 extend out laterally from 25 the sides of the pontoon at an angle for connection with the lower supporting surface 37 of the machine. At their lower ends the wires 50 are let through the sides of the pontoon for connection, inside the pontoon, 30 with the socket fittings 47 provided at the lower strut ends. This construction accords the struts 40 and 41 greater strength and eliminates the use of exposed adjusting means. The adjusting means for the wires 35 50, designated as 52, are inclosed in the pontoon and may be reached for adjustment through arm holes (not shown) formed in the side or deck of the pontoon. The fore and aft wiring 51 is similarly arranged in 40 that the ends of the wires are carried into the pontoon through the deck for connection with the lower strut ends. These wires however are provided with special strap fastenings 53 which lie upon opposite sides 45 of the center longitudinal bulk head 14 of the pontoon for connection as at 54 with the opposed fitting parts constituting the socket fittings 47. This construction is best illustrated in Fig. 6. Preferably the wires 50 and the wires 51 are attached to the fittings 47 at adjacent points. As the wires at 50 opposite sides of the pontoon are arranged in pairs obviously an individual wire or wires is or are provided for each strut. The 55 tightening means for the wires 51 are inclosed in the fuselage or body of the machine and may be reached for adjustment from the inside of the body. These wires are carried respectively to the upper end of 60 the forward strut 40 and to the rear strut 41 at a point in the horizontal plane of the longerons 24. The fitting 44 illustrated in Fig. 6 affords a connection for the wire leading to the rear center strut. The fore 65 and aft wires 51, as intimated, preferably

lie in the longitudinal vertical plane of the center line of the float and consequently in the same longitudinal vertical plane as the center struts.

A landing gear of the above construction 70 offers a minimum of resistance. The number of landing gear struts as compared with prior constructions is reduced by at least one-half. The only struts provided both lie in the longitudinal vertical plane of the 75 center line of the float and are respectively inclined and vertical, the forward strut being the inclined strut because of the fact that in planing the impacts incurred are directed in a direction more or less at an angle. The wires 50 and 51 brace the pontoon 80 against laterally directed shocks as well as in a fore and aft direction. All of said wires are carried to the lower strut ends and are let through the outer covering of the 85 pontoon whereby their adjusting means may be removed from view. The details of construction are also conducive to maximum strength as the sockets provided at the lower strut ends snugly receive the struts 90 and extend the full depth of the pontoon at its point of maximum depth. These sockets furthermore are provided at the points of intersection of the transverse bulk heads 20 with the center line bulk head 14. 95

While we have described our invention in detail in its present preferred embodiment, it will be obvious to those skilled in the art after understanding our invention, that various changes and modifications may be 100 made therein without departing from the spirit or scope thereof. We aim in the appended claims to cover all such modifications and changes.

What is claimed is:

1. A landing gear for hydroaircraft comprising a float, a plural number of struts, the struts being arranged one aft of the other in the longitudinal vertical plane of the fore and aft axis of the float, socket fittings extended deep into the float to receive the lower strut ends, and brace wires extended angularly out from the socket fittings to brace the float against laterally directed shocks. 110

2. A landing gear for hydroaircraft comprising a float, a plural number of struts, the struts being arranged one aft of the other in the longitudinal vertical plane of the fore and aft axis of the float, socket fittings 120 extended deep into the float to receive the lower strut ends, and brace wires extended angularly off from the socket fitting in a fore and aft direction to brace the float fore and aft.

3. A landing gear for hydroaircraft comprising a float, a plural number of struts, the struts being arranged one aft of the other in the longitudinal vertical plane of the fore and aft axis of the float, socket fit- 130

tings extended deep into the float to receive the lower strut ends, and brace wires extended both angularly laterally and angularly in a fore and aft direction from the 5 socket fittings to brace the float both laterally and fore and aft.

4. In a landing gear for hydroaircraft, a float, landing gear struts, and wires for bracing the float, the wires being extended 10 into the float rather than fastened upon its exterior.

5. In an airplane landing gear, a float for supporting the craft on the water, landing gear struts inclosed for a portion of their 15 length inside the float, and brace wires for the float let through the outer covering thereof for anchorage at or near the inclosed strut ends.

6. In a landing gear for hydroaircraft, a 20 float, landing gear struts carried deep into the float, the struts being arranged one aft of the other in the longitudinal vertical plane of the fore and aft axis of the float, and wires for bracing the float laterally, 25 the wires being likewise extended into the float and fixed or anchored at or near the inclosed strut ends.

7. In a landing gear for hydroaircraft, a float, a bulkhead forming a structural element 30 of the float, landing gear struts arranged one aft of the other in the longitudinal vertical plane of the fore and aft axis of the float, the lower ends of the struts being bifurcated to straddle the bulkhead, 35 and socket fittings provided one for each strut, each fitting comprising separate fitting parts disposed respectively on opposite sides of the bulkhead.

8. In a landing gear for hydroaircraft 40 comprising a float, a plural number of struts, socket fittings extended deep in the float to receive the lower strut ends, and brace wires fastened to the socket fittings to brace the float laterally and fore and aft.

45 9. In an airplane landing gear, the combination with the fuselage, of a float, a bulkhead forming a part of the structural framework of the fuselage, a bulkhead forming a part of the structural framework of the 50 float, and a strut connection between the fuselage and the strut, the ends of the strut being extended respectively deep into the fuselage and deep into the float, said extended float portion of the strut being bifurcated to 55 straddle the respective bulkheads.

10. In an airplane landing gear, a float for supporting the craft on the water, inter-

secting bulk heads forming parts of the structural framework of the float, a landing gear strut having its lower end bifurcated to 60 straddle one of the bulk heads, and a socket fitting provided at the point of intersection of the bulk heads to receive the inclosed end of the strut.

11. In a landing gear for airplanes, the 65 combination with the fuselage, of a float for supporting the craft on the water, a landing gear strut, a socket fitting inclosed in the fuselage to receive the upper strut end, and a second and similar fitting inclosed in the 70 float to receive the opposite end of the strut, the fittings in each instance being inclosed respectively in the fuselage and float and interconnected by brace wires which penetrate the outer covering of the fuselage or 75 float respectively.

12. In an aircraft, the combination of a body including a framework and an outer covering within which the framework is inclosed, a landing gear, and wires for bracing 80 the landing gear extended through the outer covering of the body for anchorage interiorly thereof.

13. In an aircraft, the combination of a float including a framework and an outer 85 covering within which the framework is inclosed, and wires for bracing the float anchored on the inside thereof and extended through the outer covering.

14. In an aircraft, the combination of a 90 body including a framework and an outer covering within which the framework is inclosed, an element fastened to the body, and a wire for bracing the element extended through the outer covering of the body for 95 anchorage interiorly thereof.

15. A landing gear for hydroaircraft comprising a float, a landing gear, a socket fitting extended deep into the float to receive the lower strut end, and a brace wire extended angularly out from the socket fitting 100 to brace the float laterally.

16. A landing gear for hydroaircraft comprising a float, a landing gear strut, a socket fitting extended deep into the float to receive the lower strut end and brace wires extended both angularly laterally and angularly in a fore and aft direction from the 105 socket fitting to brace the float both laterally and fore and aft.

In testimony whereof we hereunto affix our signatures.

WILLIAM L. GILMORE.
JOSEPH F. MEADE.
